(57) **CLAIM**

The ornamental design for a deck box, as shown and described.

DESCRIPTION

FIG. 1 is a top perspective view of a deck box, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the deck box, shown in an alternate open configuration;

FIG. 9 is a perspective view of the deck box, shown in another alternate open configuration; and,

FIG. 10 is a perspective view of the deck box, shown in another alternate open configuration.

The broken lines representing stitching are part of the claimed design.

1 Claim, 10 Drawing Sheets
